United States Patent Office.

P. D. F. GOEWEY, OF ALBANY, NEW YORK.

Letters Patent No. 82,108, dated September 15, 1868.

IMPROVEMENT IN CUPBOARD-CATCHES.

The Schedule referred to in these Letters Patent and making part of the same.

TO ALL WHOM IT MAY CONCERN:

Be it known that I, P. D. F. GOEWEY, of Albany, in the county of Albany, and State of New York, have invented a new and useful Improvement in Slide-Latches, by which the bolt may be locked, so as to keep it in place; and I do hereby declare that the following is a full, clear, and exact description of the same, so as to enable any one skilled in the art to manufacture and use the same, reference being had to the accompanying drawings, forming part of this specification, in which—

Figure 1 is a perspective view.

Figure 2 is a longitudinal sectional view.

Figure 3 is a perspective view of the bolt.

Figure 4 is a front view of the bolt.

Figure 5 is a view of the locking-tumbler.

Figure 6 is a perspective view of the frame of the latch.

Figure 7 is a similar view of the frame and tumbler, showing the position of the tumbler when the bolt is locked.

Figure 8 is an end view of the knob, looking from the back.

Figure 9 is a perspective view of the frame and tumbler, showing the position of the tumbler when the bolt is unlocked.

By reference to the drawings, it will be seen that the latch consists of a frame, A, a bolt, B, a knob, C, and locking-tumbler, D. The shape of the aperture for the locking-tumbler D is shown at E in fig. 6.

The manner of operating my invention is as follows: By turning the knob C to the left, the locking-tumbler D is brought into the position shown in fig. 7, and the bolt locked. By turning the knob C to the right, the locking-tumbler D is turned to the position shown in fig. 9, and the bolt unlocked. Then, by pressing the knob C down, the bolt B is slid out of the way.

What I claim as new, and desire to secure by Letters Patent, is—

The latch, composed of the plate A, the locking-tumbler D, in combination with and operated by the doubly-moving knob C, all constructed substantially as herein shown and described, and for the purposes specified.

P. D. F. GOEWEY.
